UNITED STATES PATENT OFFICE.

JOSEPH B. DUNLAP, OF TULSA, OKLAHOMA.

EQUALIZING PUMP-JACK.

Specification of Letters Patent.

Patented Aug. 6, 1918.

1,274,861.

Application filed July 6, 1917. Serial No. 179,081.

To all whom it may concern:

Be it known that I, JOSEPH B. DUNLAP, a citizen of the United States, and a resident of Tulsa, in the county of Tulsa and State of Oklahoma, have invented new and useful Improvements in Equalizing Pump-Jacks, of which the following is a specification.

My invention is an improvement in equalizing pump jacks, and has for its object to provide a jack wherein the frame attaches to the casing for holding the jack in alinement with the pump rod to cause the pull to be in direct alinement with the stuffing box to minimize the wear on the rod and box, and wherein a drum is provided for permitting adjustment of the stroke by engaging the line with different parts of the drum.

20 In the drawings:

Figure 1 is a side view of the improved jack;

Fig. 2 is a front view;

Fig. 3 is a front view of the equalizing drum;

Fig. 4 is a perspective view of the vibrating lever;

Fig. 5 is a similar view of one of the bearings for the sheave wheel;

Fig. 6 is a perspective view of the casing clamp.

In the present embodiment of the invention, a suitable base 1 is provided, and at one end of the said base there is a pair 35 of standards 2 which carries the sheave wheel 3, the said standards being of angular material, as shown, and arranged with one side of their angular portions parallel and with the other extending outwardly and in the same plane.

40 A bearing block 4 is provided for mounting the sheave wheel, the said block having at one end an overlying web 5, which is adapted to engage over the top of the adjacent standard, and this web is notched, as indicated at 6, to receive the outwardly extending portion of the standard. At the notch the web extends beyond the adjacent side of the block, as shown, and the block 45 is provided with an opening for receiving a reduced journal pin 7 on the end of the shaft 8 of the sheave wheel, and with smaller openings for receiving bolts 9 which connect the block to the standard.

50 55 The rope or cable 10 which connects the pump rod 11 with the vibrating lever 12

passes over the sheave wheel and about the compensating drum 13. At one end the cable is passed through an eye in the plunger stem, and at the other end through a loop 60 14 on the lever. It will be noticed that this lever has notches 15 in its opposite edges for engagement by the loop 14 and by a loop 16 which connects the lever to a suitable source of power for vibrating the lever. 65

The casing 17 for the well is engaged by the sectional bearing shown in Fig. 6 to firmly lock the pump jack to the casing. This bearing, as shown, consists of similar sections 18, each of which is recessed on its 70 inner face, as indicated at 19, for receiving the pump casing, and the sections are connected together by bolts and nuts 20. The standards are spaced apart near their upper ends by an arbor 21 which encircles a bolt 75 22 connecting the standards, and the standards are braced by inclined braces 23, between which is mounted the compensating reel 13. The braces 23 are angle bars, and on their outer faces are bearing blocks 24 for 80 the shaft 25 of the reel. These blocks, as shown in Figs. 1 and 3, have a central opening for receiving the ends of the shaft 25, and they are bolted to the vertical portion of the angle braces on the outer sides of the 85 said braces, as shown in Fig. 1.

The reel, shown more particularly in Fig. 3, has a double taper consisting of two frusto-conical portions arranged with their small ends adjacent, and the entire reel has 90 a spiral groove 26 which is continuous from one end of the reel to the other. The stroke of the pump, it will be evident, will depend upon the position of the cable 10 with respect to the reel. One end of the shaft 25 95 is polygonal, as shown at 30, for receiving a wrench in order that the shaft may be turned to bring the cable to a different portion of the drum, and the cable may be moved from place to place, that is, from the lowest to the highest or in the opposite direction, for the purpose of adjustment. The spiral groove will cause the cable to follow the groove in whichever direction the drum is turned.

100 105 Through the clamp 18, the sheave wheel is held in exact position with respect to the pump cylinder, so that the cable passes tangentially over the reel directly to the pump plunger.

I claim:

110 1. A pump jack comprising a frame hav-

- ing means at one end for clamping the frame to the well casing and having a pair of standards at the said end, a sheave wheel journaled between the standards, a cable 5 passing over the sheave wheel and connected to the plunger rod of the pump, an operating lever pivoted to the frame at the opposite end from the standards, the other end of the cable being adjustably connected to the 10 said lever, and a compensating drum journaled adjacent the standards and about which the cable passes between the sheave wheel and the lever, said drum being of smallest diameter at its center and gradually increasing in diameter toward its ends and having a spiral groove running from one end to the other. 15 5. A pump jack comprising a frame, a sheave wheel journaled on the frame, a cable passing over the sheave wheel and adapted for connection at one end to the plunger rod 40 of the pump, an operating lever pivoted to the frame at the opposite end from the sheave wheel, the other end of the cable being adjustably connected to the lever, and a compensating drum journaled adjacent to 45 the sheave wheel and about which the cable passes between the sheave wheel and the lever, said drum having a spiral groove running from one end to the other and being of largest diameter toward its ends. 20 2. A pump jack comprising a frame having means at one end for clamping the frame to the well casing and having a pair of standards at the said end, a sheave wheel journaled between the standards, a cable 25 passing over the sheave wheel and connected to the plunger rod of the pump, an operating lever pivoted to the frame at the opposite

end from the standards, the other end of the cable being adjustably connected to the said lever, and a compensating drum journaled adjacent the standards and about which the cable passes between the sheave wheel and the lever, said drum being of smallest diameter at its center and gradually increasing in diameter toward its ends and having a spiral 35 groove running from one end to the other. 3. A pump jack comprising a frame, a sheave wheel journaled on the frame, a cable passing over the sheave wheel and adapted for connection at one end to the plunger rod 40 of the pump, an operating lever pivoted to the frame at the opposite end from the sheave wheel, the other end of the cable being adjustably connected to the lever, and a compensating drum journaled adjacent to 45 the sheave wheel and about which the cable passes between the sheave wheel and the lever, said drum having a spiral groove running from one end to the other and being of largest diameter toward its ends. 25
